RAYON-SPINNING PUMP

Ivar Meurling, Swarthmore, Pa., assignor, by
mesne assignments, to American Viscose Cor-
poration, a corporation of Delaware

Application June 25, 1935, Serial No. 28,315

5 Claims. (Cl. 103—126)

This invention relates to pumps used in spinning rayon, and more particularly pumps of the gear type. One object of the invention is to produce a simplified structure which will be efficient and at the same time easy to clean. The invention will be shown and described in an embodiment more particularly intended for spinning viscose, but the invention is equally applicable to the spinning of any other solution for 10 making an artificial yarn.

In the drawings,

Fig. 1 is a plan view of the two main plates of the pump casing, opened out, showing the new open inlet and outlet grooves;

15 Fig. 2 is a horizontal section on the median line through the assembled pump, taken on the line 2—2 of Fig. 5;

20 Fig. 3 is an elevation of the pump in its operative position, partly in section, taken through the main gear shaft on the line 3—3 of Fig. 5;

25 Fig. 4 is an enlarged detail of the outlet groove and of the pump gear teeth at the point of meshing; while

Fig. 5 is an elevation of the pump from the 25 side on which the driving wheel is located.

In spinning rayon it is customary to use a pump to force the solution through the spinneret into the setting bath, and one of the more usual types for this work is the gear pump. It is essential for a pump used in spinning rayon that it deliver an absolutely uniform quantity of spinning solution continuously. In view of this fact and the fact that a viscose pump runs at a low speed, the pump must be built with great accuracy and kept perfectly clean. If a machine which is spinning rayon stops for several days, it is necessary to take the pump apart and clean it thoroughly. It is necessary to remove even the thinnest film from the passages through 35 which the solution flows in order that no difficulty shall be encountered with small bits of hardened solution when the machine starts spinning again. Heretofore it has been very difficult to clean a gear pump satisfactorily, because some of the 40 passages are inaccessible.

One of the features of my invention lies in the ease with which the pump can be cleaned. Heretofore the inlet and outlet passages for the viscose have each been bored through one of the 45 solid plates constituting the casing and the passages have come to the surface of this plate only at the pump gears. According to my invention these passages now are placed at the surface of the plates so that they form nothing but shallow 50 grooves when the casing is taken apart. It is

of course very simple to clean such open grooves and to satisfy one's self that the groove is clean. While the grooves are shown formed in one plate only, it will be obvious that the groove can be formed half in one plate and half in the juxtaposed plate.

Referring now to the drawings, the casing consists essentially of two main plates 10 and 11 with a thin center plate 12 between them. This center plate 12 has an opening in it in which lie the two gears 18, 19. The plate is about the thickness of the gears that do the pumping and permits the gears to turn, but in contact with plates 10 and 11. The gears are mounted on shafts 20, 21 respectively carried by bearings in the main plates 10, 11. The main plates 10, 11 are kept in register with each other by pins 46 lying in holes 47 at the end of the plates. All three plates are held together by screws 15 placed at any desired position around the plates, 20 these screws passing through the center plate as well as through the two outside plates. It is thought desirable to have some of the screws come in from one plate and some from the other (Fig. 1). The juxtaposed or interior faces of the 25 three plates are machined smooth and make a liquid-tight fit when the plates are screwed together. In this way the center plate serves as a closure for the grooves 13, 14 which constitute the inlet and outlet for the solution. The portion of the center plate between the two gears 18, 19 is cut away so that the area between the gears is open (Fig. 4). This opens the ends of the inlet and outlet grooves or passages sufficiently to permit the liquid to be taken by the 30 gear wheels on one side and discharged on the other. It will be observed that the solution is delivered to the gears from the plate 11 on one side 48 of the gears and at the point where the teeth are separating. The solution is carried 35 around with the teeth as they travel to the side where they mesh. On the side of the gears where the teeth mesh, the outlet passage is, of course, in the plate 10 which is the opposite side of the 40 gears from the inlet.

Referring to Figs. 1 and 2 of the drawings, it will be observed that the solution enters through a passage 16 which goes straight, i. e., without turns, through the outer casing to the inner surface thereof and from this point on until 50 the liquid is delivered to the gears of the pump, the groove is entirely open and accessible for cleaning. The construction of the pump is simplified in a number of other ways, all of which will be described in connection with the drawings. 55

It will be seen that in order to clean the pump it is necessary merely to take out the screws and separate the three plates, when all interior passages will be open and available for cleaning within sight of the operator. The portions 16, 17 of the inlet and outlet grooves 13, 14 which go straight through to the outer face of their respective plates are short and straight and can be cleaned and examined easily. By thus making open grooves of all portions of the passages going longitudinally of the plates, all difficulty in cleaning is avoided.

In a gear pump, as the teeth come together and mesh, they tend to capture some of the liquid between them so that it cannot escape. In order to avoid any undue pressure from such captured liquid, I have lengthened the discharge passage 14 until the end of the passage almost reaches the line joining the center of the two gears. This provides a simple means of releasing any captured liquid. This feature is illustrated in Fig. 4.

As already mentioned, the two gears 18, 19 are mounted on shafts 20 and 21 which has their bearings in the main plates 10 and 11. Another novel feature of my pump is the manner in which the unavoidable leakage between the gear shafts and their bearings is taken care of. My pump is not of the open type but is of the enclosed type. I provide oil pockets at the ends of the shafts and fill them with oil. I have found that due to the pressure of the oil being lower than the pressure of the pump the oil in such pockets does not penetrate through to the inside of the pump and get mixed with the solution which goes to the spinneret. On the other hand, any spinning solution which forces its way between the shafts and their bearings will be kept in a soft condition by the oil in the pocket, and thus I prevent any hardening of the solution.

The bearings will now be described, those in the plate 10 being described first. In this plate are circular holes 43 in which turn the shafts 20 and 21 for the gears. The bearings fit the shafts as closely as is possible. These openings or holes through the plate 10 terminate in a pocket at the outer edge of the plate for a purpose. In the machine shown in the drawings this pocket is formed of a circular recess 24 connected to the shaft bearings 43 and enclosed by a cover plate 22 held to the main plate by a screw 23. The pocket 24 thus formed is liquid-tight and I fill it with oil. I find that this oil prevents any solution which comes through the bearings from hardening. The cover of the oil pocket can be removed if desired. The normal process of cleaning out the pocket—which does not require removal of the cover—will now be described.

This oil pocket 24 can be seen in Figs. 2 and 3 of the drawings. Referring more particularly to Fig. 3, it will be observed that the oil pocket is connected to an auxiliary reservoir 25 which leads to an oil cap 26 on the upper side of the main plate 10. By opening the oil cap 26 and dropping oil into the reservoir 25, the pocket 24 can be kept full of oil. It has further been discovered that if the oil used is of higher specific gravity than the spinning solution, the spinning solution will tend to rise into the oil reservoir 25 and can be removed. This need be done only at long intervals. By following out this method of operation it is necessary to remove the cover plate 22 only for inspection purposes.

The pump is driven by a gear 27 fastened on the outer surface of the main plate 11. This driving gear can be seen in Figs. 2, 3 and 5 of the draw-

ings. The outer surface of the plate 11 with which the driving gear is in contact is carefully machined. The driving gear 27 is held on the surface of the main plate 11 by means of a thrust screw 30 carried by a cover 28. In this way a liquid-tight seal is formed between the driving gear and the outer surface of the main plate 11. The cover 28 overlies nearly all of the driving gear 27, and it is fastened to the main plate 11 by means of three screws 31. It will be observed that by means of this simple arrangement the gear is protected.

In the center of the driving gear 27 is fixed a hollow sleeve 32. Lying diametrically across the inside of this sleeve is a pin 33. The end of the long gear-shaft 21 is slotted at its outer end to receive this pin 33, a slotted connection thus being made between the driving gear 27 and the shaft of one of the gear wheels. The sleeve 32 extends into a recess 34 in the outer face of the main plate 11. This recess acts as an oil pocket. The recess and the extension of the sleeve fit together snugly and keep the gear centered. The sleeve, however, does not occupy the entire space formed by this recess 34, as can be seen from Fig. 2 of the drawings. To provide an adequate bearing for the shaft 21 in the plate 11, there is a boss 35 which can extend into the recess 34 to a point practically level with the adjacent outer surface of the casing. The sleeve 32 does not contact with this boss but leaves room for circulation of oil between the boss and the sleeve. The bearing for the short shaft 20 of the gear 18 can for convenience be bored completely through the main plate 11, but if it is bored through it is covered liquid-tight by the driving gear 27, as in the case of the other bearing. There is an opening 36 from the space at the end of the short shaft 20 which provides a communication between the recess 34 and the end of the bearing for the shaft 20. The shaft 20 does not extend to the outer face of the main plate 11, thus affording room for circulation of oil opposite the end of the shaft.

There is an oil reservoir 37 in the plate 11 which is connected to an oil cap 38 on the top of the plate (Fig. 3). This reservoir connects with the recess 34 and any dribbles of spinning solution tend to pass up to the reservoir. In addition there are holes 39 at diametrically opposite points in the sleeve 32 which permit passage of oil from the space between the sleeve and the boss 35 to the passage 36 on the outside of the sleeve 32. These holes 39 also serve to lubricate the bearing between the sleeve and the recess 34. The holes are connected on the outside of the sleeve by a circumferential groove 44. It will be observed that the circulation of oil will take care of both bearings.

It will be noted that the sleeve 32 has a flange 40 overlying the outer side of the driving gear 27 and that there is a closure 41 permanently inserted in the center of this sleeve (Fig. 2). This closure also has a shoulder or flange 42 overlying the outer face of the sleeve 32, and this closure contacts with the end thrust screw 30 on the cover 28. It will be observed that with this overlapping shoulder or flange arrangement of the closure and sleeve the end thrust screw 30 located outside the gear 27 has a direct pressure on the driving gear, pressing it against the smooth outer face of the casing so as to make the closure liquid-tight. The end thrust screw 30 has a lock nut 45 on the outside of the cover to permit adjustment of the screw.

To disassemble the driving mechanism it is

necessary merely to unscrew the three screws holding the cover onto the main plate 11 and the driving gear 27 can be removed, giving access to the recess 34 for inspection as well as for examination of the driving gear itself.

I have discovered that it is unnecessary to have the two main plates of maximum thickness throughout. Thus while it is necessary for the portion of the plate which contains the bearings 10 and the oil pockets to be of a certain thickness, the portion of the plates where the spinning solution inlet 16 is located and the spinning solution outlet 17 need not be of any such thickness. I have discovered that it is better to make this portion of each plate much thinner, thus making the holes through the plates shorter and easier to clean.

The path of the spinning solution through the pump is as follows. The spinning solution enters 20 at the passage 16 in the main plate 11 (Figs. 2 and 3) and goes from there direct to the inner face of the plate 11 where it traverses the inlet groove 13 to a position beside the gear wheels 18 and 19. At this position the gear teeth are 25 turning away from each other, that is to say, on the upper or inlet side 48 as the gears are shown in Fig. 4, and the solution is therefore taken between the teeth of the gears 18 and 19 and the center plate 12. The solution is carried around 30 until it comes to the discharge or outlet side, where it meets the outlet groove 14 (Figs. 1 and 4). As already mentioned, this groove extends beside the gear wheels to a point almost reaching the line joining the centers of the two gears so 35 that any liquid which may be imprisoned between the teeth is expelled laterally into the outlet groove 14. The spinning solution passes along this outlet groove until it comes to the short passage 17 leading through the main plate 10, where 40 it is discharged from the pump. Owing to the pressure under which the solution is moving through the pump, there always is a slight leakage through the bearings of the gears, as already mentioned. This inevitable leakage goes into the 45 oil-filled pockets 24 and 34, the leakage always being kept soft by the presence of the oil. The oil pockets and oil reservoirs are large enough so that it is necessary to clean out or get rid of the surplus spinning solution only at long intervals.

50 It will be seen that the pump is composed of a minimum number of parts which can be assembled and disassembled with great ease and that it is not necessary in the ordinary running of the pump to disassemble it at all. If for any reason 55 the pump is stopped and it is necessary to clean it, it can be disassembled very easily and the inlet and outlet passages and all other passages through which the solution passes are easily accessible and in fact laid open to the operator. 60 The only passages which are not open on one side throughout their length are the two short passages 16 and 17 passing through the thin portions of the main plates 10 and 11 from one side to the other.

What I claim is:—

1. In a gear pump for a rayon spinning ma-

chine, pump gears, shafts carrying said gears and a casing surrounding and forming bearings for said shafts, in combination with a gear outside the casing adapted to engage and drive the end of one of the shafts, and a non-revoluble 5 guard for the driving gear mounted on the casing outside the gear covering the latter and pressing it against the casing.

2. In a gear pump for a rayon spinning machine, pump gears, shafts carrying said gears, a 10 casing surrounding said gears and forming bearings for the latter, and an oil pocket surrounding one of the ends of said shafts and adapted to receive any spinning solution which comes through the bearing and prevent it from 15 hardening, in combination with a gear adapted to drive the shaft end and to serve as a closure for said oil pocket, and means acting on the outer side of said gear adapted to hold same in liquid-tight contact with the casing. 20

3. In a gear pump for a rayon spinning machine, pump gears, shafts carrying said gears and a casing surrounding the latter and forming bearings for the shafts, in combination with an oil pocket for the end of one of said shafts 25 having an oil opening above the level of the shafts, a gear adapted to engage and drive the shaft end and to serve as a closure for said oil pocket, and means acting on the outer side of said gear to hold same against said casing. 30

4. In a gear pump for a rayon spinning machine, pump gears, shafts carrying said pump gears and a casing surrounding said gears and forming bearings for said shafts, said casing being formed of plates with open grooves on 35 juxtaposed faces serving as passages for the spinning solution to and from the gears, said bearings and shafts permitting a trace of spinning solution to come through to the outside of the bearings for lubrication, in combination with an oil pocket whose oil is in contact with the bearing end of one of said shafts to make the leaking solution harmless, a revolving gear adapted to engage and drive said shaft end and serving as a closure for said oil pocket, and 40 means mounted exterior of said shaft, oil pocket and gear, holding the latter removably against the casing to close the oil pocket.

5. In a gear pump for a rayon spinning machine, pump gears, shafts carrying said pump 50 gears and a casing surrounding said gears and forming bearings for said shafts, said bearings and shafts permitting a trace of spinning solution to come through to the outside of the bearings for lubrication, in combination with an oil 55 pocket whose oil is in contact with the bearing end of one of said shafts to make the leaking solution harmless, a revolving gear adapted to engage and drive said shaft end and serving as a closure for said oil pocket, and means mounted 60 exterior of said shaft, oil pocket and gear, holding the latter removably against the casing to close the oil pocket.

IVAR MEURLING. 65
